GANG FISHHOOK GUARD

Roy D. Chancellor, 1266 Naglee, San Jose, Calif.

Filed July 9, 1963, Ser. No. 75,714

Term of patent 14 years

(Cl. D31—4)

FIG. 3

I claim:

An ornamental design for a gang fishhook guard, as shown.
